UNITED STATES PATENT OFFICE

2,526,589

EARTH MOVING OR LEVELING MACHINE

Ray E. Stevenson, Seattle, Wash.

Application December 27, 1946; Serial No. 718,837

1 Claim. (Cl. 37—144)

1

My invention relates to a machine for moving or leveling earth, and the like.

An important object of my invention is to provide a machine for moving or leveling earth, including a tractor, and having hydraulically operated means for raising and lowering the leveling blade or mold-board.

A further object of the invention is to provide an earth moving machine of the character mentioned, in which the hydraulic mold-board adjusting means are arranged in such a manner that they are out of the field of vision of the operator, and tend to concentrate weight near the center of gravity of the tractor.

A further object is to provide a closed hydraulic system for moving the leveling blade or mold-board, which system is simple and positive in operation.

A still further object of my invention is to provide a machine for moving earth, and the like, which is relatively simple in construction, and inexpensive to manufacture.

Other objects and advantages of the invention will be apparent during the course of the following description.

In the accompanying drawings, forming a part of this application, and in which like numerals are employed to designate like parts throughout the same,

Figure 1 is a plan view of the earth moving machine embodying my invention,

Figure 2 is a side elevation of the same,

Figure 3 is a plan view of the U-shaped frame and mold-board removed, parts broken away,

Figure 4 is a vertical section taken on line 4—4 of Figure 3;

Figure 5 is a fragmentary vertical section taken on line 5—5 of Figure 2;

Figure 6 is a schematic diagram of the hydraulic system,

Figure 7 is an end elevation, diagrammatic in form, of a control valve,

Figure 8 is a longitudinal section taken on line 8—8 of Figure 7,

Figure 9 is a longitudinal vertical section taken on line 9—9 of Figure 7, and

Figure 10 is a horizontal longitudinal section taken on line 10—10 of Figure 7.

In the drawings, where for the purpose of illustration, is shown a preferred embodiment of my invention, the numeral 15 designates a tractor, including a chassis 16, suitably supported by wheels 17, carrying "Caterpillar" treads 18. Disposed near and outwardly of the wheels 17 are longitudinal rails 19, which are preferably chan-

2

nel-shaped in transverse cross section. Longitudinal angle-irons 20 are arranged beneath the rails 19, and suitably rigidly secured thereto. The rails 19 are arranged upon opposite sides of the tractor, and carry bearings 21, which are rigidly secured to the rails, and which receive pins 22, rigidly secured to supports 23. These supports 23 are fixed to the chassis 16. The rails 19 are horizontal, and are provided at their forward ends with upstanding bearings 24, which rotatably receive pins or hub extensions 25, of the front wheels 17. It is thus seen that the rails 19 are suspended from the chassis of the tractor, and are held against movement relative thereto.

Arranged near the forward end of the tractor, and extending forwardly of the same is a U-shaped frame 26, including parallel longitudinal main arms 27, and a forward transverse beam 28, secured to the forward ends of the main arms 27 by means of welding, or the like. The frame 26 further includes a pair of horizontal diagonal braces 29 arranged near the forward end of the frame, the ends of which are rigidly secured to the main arms 27 and to the beam 28 by means of welding, or the like. Rigidly secured to the ends of the beam 28 and to the outer sides of the main arms 27, near their forward ends, are vertical side plates 30. These plates 30 form the sides for a curved mold-board or plate 31, and this mold-board is arranged between the side plates 30 and its ends are rigidly secured to the side plates by means of welding, or the like. Rigidly secured to the rear surface of the mold-board 31, and extending longitudinally of the mold-board 31, and flush with its upper edge, is a stiffener plate 32. Rigidly secured to the rear surface of the mold board and to the rear side of the stiffener plate 32 are forwardly upwardly inclined braces 33, the lower ends of which are rigidly secured to the arms 27, by means of welding, or the like. The mold-board 31 is provided with a scraper plate or blade 34, rigidly secured to the mold board, near the lower longitudinal edge of the same, by means of bolts, or the like. This blade 34 extends for the entire length of the mold board. Arranged near the rear ends of the main arms 27, and rigidly secured thereto by means of welding, or the like, are parallel rearwardly upwardly inclined lever arms 35, the upper ends of which terminate rearwardly of the main arms 27 and substantially at the top of the tractor chassis 16. Rigidly secured to the upper surfaces of the main arms 27, and to the forward inclined surfaces of the lever arms 35 are stiff-

fener webs 36. The rear ends of the main arms 27 carry suitable bearing blocks 37.

Mounted upon the rails 19, and rigidly secured thereto by means of bolts 38, or the like, are vertical jack mounting brackets 39, having inwardly extending transverse mounting extensions 40, and depending extensions 41. Mounted within openings formed in the depending extensions 41, are pivot pins 42, which extend through the bearing blocks 37. Attached to the jack mounting brackets 39, near their upper ends, by means of bolts 43, or the like, are offset jack mounting brackets 44.

The numeral 45 designates hydraulic jacks, provided near their rearward ends with opposed horizontal trunnions 46, which extend through aligned openings in the jack mounting brackets 39 and the offset jack mounting brackets 44. Each hydraulic jack 45 includes a cylinder 47, and a reciprocating plunger 48, which is rigidly secured to the forward end of a plunger rod 49. Each plunger rod 49 extends longitudinally rearwardly of its associated jack cylinder 47, and has pivotal connection with the upper end of the adjacent lever arm 35, at 50.

Arranged at the rear of the tractor is a liquid holding tank 51, secured thereto by suitable means, and having an outlet pipe 52 which leads to a rotary pump 53. This rotary pump is rigidly mounted upon the chassis 16, at its rear end. The pump 53 has an outlet connection 54 and an intake connection 55.

Arranged near and in advance of the pump 53 is a valve 56, including a horizontal casing 57, having ports 58 and 58'; and ports 59 and 59', Figure 10. The valve casing is fixedly mounted upon the chassis by any suitable means. Mounted to turn within the case 57 is a valve element 60, having a pair of transverse parallel ports 61 and 62, Figure 10. The valve element has a longitudinal bypass port 63, Figure 8. The valve element 60 has a pair of diagonal ports 64 and 65, which cross but do not communicate with each other. The ends of the ports 63, 64 and 65 pass through the periphery of the valve element. The horizontal valve element 60 is turned by a handle 66, arranged in convenient reach of the operator upon the seat 67. A pipe 68 is secured to the connection 54 and is connected with the casing 51 and leads into the port 58. A pipe 69 is secured to the connection 55 and is connected with the casing 57 and communicates with the port 59. These pipes 68 and 69 are preferably flexible hose. A pipe 70 is connected with the casing 57 and leads into the port 58'. This pipe is connected with and leads into the forward ends of the jack cylinders 45 and 47. This pipe includes rigid pipe sections 71 and 72, connected by flexible hose 73. A pipe 74 is connected with the casing 57 and leads into the port 59' and this pipe is connected with and leads into the rear ends of the jack cylinders 45 and 47. This pipe 74 includes a rigid pipe section 75 and flexible hose connections 76.

The operation of the machine is as follows:

When the handle 66 is swung rearwardly, the port 61 registers with ports 58 and 58', and the port 62 registers with ports 59 and 59'. The liquid under pressure will be supplied from the outlet side 54 of the pump 53 and will pass through pipe 68, through the port 61, pipe 70 and into the forward ends of the jack cylinders 45 and 47. The entire system is filled with the liquid and the liquid at the rear of the plungers 48 of the jack cylinders 45 and 47 will pass through pipes

74 and 75, and through the port 62 of the valve and enter the suction end of the pump through pipe 69 and connections 55. The two plungers 48 are moved rearwardly in unison, and swing the forward end of the mold-board carrying frame upwardly. This action will continue until the ports 58' and 59' are closed, which is effected by swinging the lever 66 further rearwardly to bring the ends of the bypass port 63 into registration with the ports 58 and 59. The frame is now locked in the raised adjusted position. The fluid from the pump will now circulate through the pipe 68, port 58, port 63, port 59 and through pipe 69 back to the pump. To lower the frame 26, the handle 66 is swung forwardly to bring one end of the port 65 into registration with the port 58 and its opposite end into registration with the port 59', and one end of the port 64 into registration with the port 58' and its opposite end into registration with the port 59. The fluid now passes from the discharge side of the pump 53, through port 58 and port 65 to the rear end of the jack cylinders 45 and 47 through pipes 74 and 75. The fluid passes from the forward ends 25 of the jack cylinders 45 and 47 and passes through the pipes 71 and 70 and enters the suction end of the pump through the port 64, port 59 and through the pipe 69 to the intake side of the pump. The plungers 48 are now moved forwardly in unison and the frame 26 is lowered. When the handle 66 is again swung rearwardly the ports 58' and 59' are closed to lock the frame 26 in the adjusted lowered position and the bypass port 63 is placed in communication with the ports 58 and 59, to bypass the fluid between the outlet and inlet sides of the pump. The jack cylinders 47 swing vertically upon their pivots during the raising and lowering of the frame 26. The tractor is moved forwardly and steered in the usual manner.

It is to be understood that the form of my invention herewith shown and described is to be taken as a preferred example of the same and that various changes in the shape, size, and arrangement of parts may be resorted to without departing from the spirit of my invention or the scope of the subjoined claim. While it is preferred to use the valve shown and described, different types of valves for accomplishing the same purpose may be used.

Having thus described my invention, what I claim is:

An earth moving machine comprising a tractor including a main frame, substantially horizontal support rails disposed adjacent to the opposite sides of the tractor and extending longitudinally of the tractor and disposed laterally outwardly of the opposite sides of the main frame and secured to the main frame, a single substantially vertical flat bracket plate secured to the top of each horizontal support rail and projecting above the same for a substantial distance, the bracket plates being laterally oppositely disposed and including flat depending integral extensions 65 disposed adjacent to the outer faces of the support rails, said depending extensions having their bottoms terminating adjacent to the bottoms of the support rails, separate jack cylinder mounting brackets detachably secured to the outer sides 70 of the bracket plates near the tops of the bracket plates and including integral laterally outwardly offset substantially vertical portions which are adjacent to the tops of the bracket plates and spaced laterally outwardly thereof, generally horizontal vertically swingable jack cylinders ar-

ranged between the tops of the bracket plates and said vertical portions and pivotally connected near their rear ends only with the tops of the bracket plates and vertical portions, reciprocatory plungers mounted within the jack cylinders and including rods which extend longitudinally rearwardly of the tops of the bracket plates and vertical portions, a generally horizontal U-shaped frame including side arms disposed adjacent to the outer faces of the vertical bracket plates and substantially at the elevation of the depending extensions of the bracket plates, the rear ends of the side arms being pivotally secured to the depending extensions of the bracket plates so that the U-shaped frame may swing vertically, a blade secured to the forward end of the U-shaped frame, single upstanding rearwardly inclined lever arms secured to the side arms of the U-shaped frame and disposed near the outer faces of the bracket plates and having their top ends disposed substantially at the ele-

5 vation of the tops of the bracket plates and vertical portions, the upstanding lever arms being arranged transversely between said bracket plates and the offset upstanding portions, the tops of the lever arms being pivotally connected with the rear ends of the rods, and fluid pressure means connected with the jack cylinders for causing the plungers to move in unison in either direction for raising and lowering the U-shaped frame.
